TREATMENT OF HYDROCARBONS

Pike H. Sullivan, New Rochelle, N. Y., assignor to
 Gasoline Products Company, Inc., Newark, N. J.,
 a corporation of Delaware

Application March 21, 1933, Serial No. 661,868

4 Claims. (Cl. 196—9)

The present invention relates to an operation for the production of a superior anti-knock motor fuel product from hydrocarbon materials, and more particularly relates to the treatment 5 of normally liquid hydrocarbon materials of the gasoline type, for example naphtha, gasoline, etc., and normally gaseous hydrocarbon materials, for the production of anti-knock motor fuel of the gasoline type. The normally gaseous hydrocarbon materials may comprise those of the saturated or paraffin series, such as methane, ethane, propane, butane, pentane, and the like, or those of the unsaturated type, such as ethylene, propylene, isopropylene, butylene, etc., which are generally designated as "olefins".

In the conversion of more or less saturated hydrocarbon gases into liquid products, two distinct types of reactions take place. These reactions comprise the splitting or cracking of the 20 saturated molecules into unsaturated products such as olefins, and the combination or interaction of such unsaturated products for the formation of heavier or higher boiling liquid products, respectively.

25 My invention contemplates subjecting light hydrocarbon oil, such as naphtha or gasoline of low anti-knock value, to conditions of temperature and pressure to effect a transformation into constituents of increased anti-knock value, commingling the resultant reformed or partially reformed products with normally gaseous unsaturated hydrocarbons such as olefins or a gas or gases containing the same in substantial proportions, subjecting the commingled products to conditions of temperature and pressure effective to promote polymerization of unsaturated hydrocarbons, such as olefins, with or without further reforming of the naphtha, effecting inter-reaction or cross reaction (including polymerization) 30 between the more or less unstable unsaturated hydrocarbon constituents of the gas and the naphtha, and fractionating of the resultant products to recover useful hydrocarbon oils therefrom.

45 My invention also contemplates the use of gases initially containing only small amounts of unsaturated hydrocarbon constituents, but containing certain other hydrocarbon constituents, after subjecting same to a preliminary pyrolysis 35 to promote the formation of unsaturates such as olefins, the gaseous products of this pyrolysis, with or without removal of normally liquid hydrocarbons therefrom, being commingled with reformed or partially reformed naphtha under 40 conditions recited above.

In the reforming stage of my process, I employ low-boiling hydrocarbon oil, preferably of such character as is ordinarily designated as naphtha. Thus, I may employ any virgin or cracked naphtha, or any material having a boiling range within 5 that of the hydrocarbon oils generally designated as naphthas. For example, I may employ an oil consisting of the heavy ends of the usual naphtha fraction and having a boiling point range of from 275° to 450° F.

10 While various temperatures and pressures have been proposed and employed for the reforming of hydrocarbon oils of this character, I prefer to employ temperatures of from 900° F. to 1000° F., and pressures of from 150 to 1000 15 pounds per square inch. The temperatures may be somewhat lower than those given, for example, approaching 800° F., under a high pressure of, for example, 750 to 1000 pounds per square inch or higher, but on the other hand higher temperatures of from 1000° F. to 1300° F. may be employed with relatively low pressures.

20 I prefer to limit the time of the initial naphtha-reforming operation prior to the commingling of the treated or partially treated products with hydrocarbon gases to such extent that a partial reforming effect or conversion is obtained which is somewhat less than the effect ordinarily obtained, or desired, in reforming operations, in order that the remainder of the reforming or 25 conversion of the naphtha may be carried out in the presence of the hydrocarbon gases, although I do not limit myself to any particular extent of reforming prior to the point at which 30 the naphtha is commingled with gaseous hydrocarbons.

35 The normally gaseous hydrocarbons which I prefer to employ are those gases containing substantial amounts of unsaturated hydrocarbon constituents, such for example as ethylene, propylene, and other olefins. The larger the content of such unsaturated hydrocarbons in the gas or gases employed, the more effective are the results obtained, but ordinarily I prefer to employ 40 gases containing not less than 10% and preferably 25% or more of unsaturates.

45 Certain hydrocarbon gases, for example those gases produced in relatively high-temperature oil-cracking operations carried out in the vapor phase at temperatures of 1000° F. or higher, 50 ordinarily contain large amounts of unsaturates and may be employed directly.

55 However, as indicated hereinabove, I may initially employ gases containing only small amounts of unsaturates or even initially con-

taining substantially no unsaturated constituents, these gases being subjected to pyrolysis for the production of unsaturates before being commingled with the reformed or partially reformed naphtha.

Thus, I may employ gases containing substantial amounts of normally gaseous paraffin hydrocarbons, preferably those containing two or more carbon atoms such as ethane, propane, and butane. Methane, having a single carbon atom and being of a comparative refractory nature in so far as conversion to unsaturates is concerned, is less desirable but may be present with other more desirable constituents such as ethane.

As sources of such paraffin hydrocarbon or other hydrocarbons capable of conversion to unsaturates such as olefins, I may employ natural gas or gases derived from the destructive distillation of hydrocarbon materials, such as coal and mineral oil. I may employ substantially "dry" gases resulting from the more or less drastic cracking of petroleum oil, or mixtures of liquefiable hydrocarbons, such for example as "stabilizer reflux" containing considerable amounts of butane and pentane. Of gases derived from the decomposition of coal, the so-called "low-temperature-carbonization" coal gas is the most suitable.

When such gases do not contain sufficient quantities of unsaturated gaseous hydrocarbons, they are first subjected as aforesaid to pyrolysis under elevated temperature for the purpose of increasing their content of unsaturated gaseous hydrocarbon materials. The temperatures employed in this gas pyrolysis stage may vary considerably depending upon the nature of the gases being treated. Temperatures of from 1100° to 1750° F. are suitable, but I prefer to employ temperatures of from 1350° to 1600° F. The pressure in the gas pyrolysis stage may also vary over a wide range, but in general I prefer to use relatively low pressures of from atmospheric to 150 pounds per square inch gauge pressure, although considerably higher pressures may be employed when so desired.

The pyrolyzed gases are then mixed with the products from the naphtha-reforming stage and the commingled products are digested or reacted under elevated pressure and temperature to promote interreaction between more or less unstable constituents, as well as further reforming of the naphtha if desired. The temperatures and pressures employed in this digestion stage may be substantially the same as those employed in the zone in which the naphtha is subjected to conversion or reforming; however, satisfactory results may be secured by maintaining in this digestion stage temperatures of from about 700° to about 1000° F., and any superatmospheric pressure, preferably a pressure of from about 750 to about 1000 pounds per square inch.

Where the pressure in the gas pyrolysis stage is equal to that employed in the digestion stage, the gaseous products from the pyrolysis stage may be delivered directly to the digestion coil or vessel with naphtha from the reforming stage. When the gas pyrolysis pressures are only a little lower than those which obtain in the reforming stage, the pressure of the products from the latter stage may be utilized, as for example by means of an injector for drawing the pyrolyzed gases into the digestion stage. Ordinarily however, since it is preferred to conduct the gas pyrolysis at relatively low pressures, and since the temperatures of the pyrolyzed gases are quite high, I prefer to adopt one of two expedients

for forcing the pyrolyzed gases into the high-pressure digestion stage.

The first of these expedients consists of quenching the hot pyrolyzed gases with cool naphtha to such an extent as to reduce their temperature to such an extent as to substantially check undesired further conversion thereof and facilitate compression thereof, the mixture of pyrolyzed gases and naphtha being then delivered to the digestion stage together with the partially converted products from the naphtha-reforming stage. In some instances, this quenching may have the added advantage that it serves to check or arrest the progress of the conversion of the hydrocarbon gases in such manner as to promote further conversion and reaction in the subsequent digestion stage.

As an alternative expedient, which I prefer to employ when the pyrolyzed gases contain considerable amounts of normally liquid constituents, the pyrolyzed gases may be cooled to effect the separation of normally liquid constituents thereof and then raised to the requisite pressure and, preferably after being preheated, are delivered to the digestion stage.

The products from the digestion stage are removed and fractionated to recover valuable light oils such as naphtha or gasoline therefrom. Other products such as fuel oil, gas oil, and heavy naphtha may also be recovered, as well as fixed gas, and all or a portion or portions of these may be recycled through the earlier stages of the process for further treatment.

In order that my invention may clearly be set forth and described, I now describe, with reference to the drawing accompanying and forming a part of this specification, various preferred forms and manners in which my invention may be employed and practiced. In this drawing,

The single figure is a more or less diagrammatic view of a system for pyrolytic conversion of hydrocarbons in accordance with my invention.

Referring now to the drawing, a low-boiling hydrocarbon oil of the naphtha or gasoline type, for example an oil consisting of the heavy ends of a naphtha fraction derived from a hydrocarbon oil cracking operation and having a boiling-point range of from 300° to 450° F., is drawn from a suitable source, such as a storage vessel 1, and delivered by means of a pump 2 through a conduit 3 having a valve 4 to pipe coils 5 and 6 located within a suitable heating furnace structure 7.

During its passage through the coils 5 and 6 the naphtha is subjected to elevated temperature and pressure conditions to effect a transformation into constituents of increased anti-detonating character, for example, a temperature of about 950° F. and a pressure of from 200 to 1000 pounds per square inch.

The reformed or partially reformed products from the coils 5 and 6 pass through a conduit 8 to a mixer 9, which may take the form of an injector of conventional type, where they are commingled with normally gaseous hydrocarbons containing unsaturated hydrocarbon constituents entering the mixer 9 through a conduit 10. The commingled gases and naphtha then pass through a conduit 12 into a digestion coil 13 where they are maintained at reaction temperatures, of, for example, from 800° to 1000° F., preferably under a pressure as high as that obtaining in the coils 5 and 6. The coil 13 may be located, as shown, in a furnace structure 14

when additional heating is required at this point, while on the other hand the coil 13 may simply be insulated or even cooled where it is desirable to limit the temperatures in the digestion stage to those obtaining in the earlier stages or to even lower temperatures. Moreover, in place of the coils 13 the digestion or inter-reaction of the commingled gases and naphtha may be accomplished in an enlarged chamber, if desired.

10 The products from the coil 13 pass through a conduit 16, which may be provided as shown with a pressure-reducing valve 17, to a fractionating tower 20 which, in the instance illustrated, is provided with baffles 21, trap-out trays 15 22 and 22a, plates or bubble trays 23 and a cooling or trimming coil 24. It will, however, be obvious to those skilled in the art that the details of the fractionating apparatus may vary considerably from the preferred form illustrated in 20 the drawing.

Due to the cooling effect produced by the coil 24 through which is circulated a suitable cooling fluid, such for example as naphtha to be reformed in the coils 5 and 6, fractionation of the 25 products of reaction from the coils 13 takes place in the tower 20. Relatively heavy oil suitable for use as fuel oil may be withdrawn from the bottom of the tower through an outlet 26 having a valve 27, while an intermediate cut such as 30 gas oil may be withdrawn from the trap-out tray 22 through a valved conduit 28a. A lighter intermediate cut, such as insufficiently reformed heavy naphtha, may be collected on the tray 22a and withdrawn therefrom through a conduit 28. 35 All or any desired portion of this intermediate cut may be diverted through a branch conduit 31 having a valve 32 and leading to the intake side of the pump 2. The oil thus diverted through the conduit 31 is recycled through the coils 5 and 40 6 for further treatment. All or any desired portion of the stock withdrawn from tray 22a may be discharged from the system through a valved line 29.

The uncondensed vapors reaching the top of 45 the fractionating tower 20 and ordinarily comprising hydrocarbon constituents desirable as motor fuel and having end points as high as from 400° to 430° F., pass through a vapor line 33 to a condenser 34 provided with a valved inlet 35 50 and an outlet 36 for cooling fluid such as water. Condensate from the condenser 34 passes through a conduit 37 to a separator 38 from which normally liquid hydrocarbon oil such as naphtha or gasoline may be withdrawn through an outlet 55 55 39 having a valve 40, while uncondensed gases are removed through a conduit 42 having a valve 43.

Where the gases initially employed are to be subjected to pyrolysis for the purpose of increasing their content of unsaturated hydrocarbon, such gases are withdrawn from a suitable storage vessel 50 through a conduit 51 having a valve 52 and are delivered by a pump 53 to pipe coils 54 and 55 located within a suitable furnace structure 56.

In the coils 54 and 55, the gases are brought to suitable temperature and pressure for the formation of unsaturated hydrocarbons, for example a temperature of from 1100° to 1750° F. and a 70 pressure of from atmospheric to 150 pounds per square inch. The pyrolyzed gases may then pass through a conduit 57 having a valve 58 and the conduit 10 for admixture in the mixer 9 with naphtha from the coils 5 and 6 and delivery to the digesting coil 13. However, the valve 58

may be kept closed and the pyrolyzed gases withdrawn through a branch conduit 61 having a valve 62 and commingled with cooled naphtha drawn from the storage vessel through a conduit 63 having valves 63' and 64 and a pump 65. 5 The resultant cooled commingled material may then be delivered by means of a pump 67 through a conduit 68 and the conduit 10 to the mixer 9.

As an alternative procedure which, as has been indicated hereinabove, may be desirable when the 10 products from the coils 54 and 55 contain normally liquid hydrocarbon constituents, the valves 58 and 62 may be closed and the products from the coils 54 and 55 may then be withdrawn through a conduit 70 having a valve 71, kept 15 open in this instance, and passed through a heat exchanger 72 and a conduit 73 to a condenser 74. The condenser 74 is provided with a valved inlet 75 and an outlet 76 for cooling fluid such as water. If desired, to check undesired further 20 conversion thereof the hot stream of gases flowing to heat exchanger 72 may be cooled by introducing cold naphtha, or other cool fluid, into the stream of gases by means of the lines 63 and 61, valve 68' being closed and valves 63' and 25 62 being opened.

The cooled products pass from condenser 74 through a conduit 78 into a separator 79, from which liquid condensate may be removed through an outlet line 80 having a valve 81, while the 30 uncondensed gaseous products pass through a conduit 82 having a valve 83 to a pump 84 where they are compressed and delivered through a conduit 85, the heat exchanger 72, a conduit 86 and the conduit 10 to the mixer 9.

A portion or all of the gas removed from the separator 38 may be withdrawn through a conduit 90 having a valve 91 and leading to the intake side of the pump 53, by means of which this gas is recycled through the pyrolysis coils 54 and 55.

According to my process, a naphtha having an insufficient anti-knock value may advantageously be reformed and converted into a naphtha having a higher anti-knock value, while at the same time additional quantities of motor fuel of high anti-knock value are produced through reaction of constituents of the naphtha undergoing reformation with more or less unstable unsaturated hydrocarbons of a normally gaseous character.

While I have indicated that the pressure conditions within the digestion- or reaction-passageway 13 should be as high as those maintained within the naphtha-reforming coils 5 and 6, it 55 is to be understood that considerably higher operating pressures may be used. Under some conditions of operation it may be found desirable to employ considerably higher pressures than those maintained in the coils 5 and 6, for example, pressures of the order of from 2000 to 3000 pounds per square inch within the passageway 13, while temperatures of from about 600° F. to about 1100° F. may be employed. Suitable compressing means, such, for example, as that already described for effecting compression of the gaseous products from the coil or passageway 55, may be employed for elevating the pressure of the stream of reformed naphtha products and forcing the same into the passageway 13 60 under such increased pressures.

It will be obvious to those skilled in the art that my process is susceptible of considerable modification in detail, and my invention is therefore not limited to the specific details of the 75

example or examples given hereinabove by way of exemplification, but may variously be embodied within the scope of the claims herein-after made.

5 I claim:

1. The process which comprises subjecting naphtha to a temperature of from 900° to 1000° F. in the absence of normally gaseous hydrocarbons and substantial amounts of higher-boiling constituents to reform said naphtha, subjecting hydrocarbon gases containing paraffin hydrocarbon constituents free of products of combustion to a temperature of from 1100° to 1750° F. to promote the formation of unsaturated hydrocarbons, quenching the resultant gaseous products with cool naphtha, commingling admixed gaseous products and naphtha with the hot products from said reforming stage and digesting the commingled products at a temperature of from 700° to 1000° F. to promote interaction between unsaturated hydrocarbon constituents of said commingled products, withdrawing the resultant products and fractionating them to recover normally liquid products therefrom.
2. The process which comprises subjecting naphtha to a temperature of from 900° to 1000° F. in the absence of normally gaseous hydrocarbons and substantial amounts of higher-boiling constituents to reform said naphtha, subjecting hydrocarbon gases containing paraffin hydrocarbon constituents free of products of combustion to a temperature of from 1100° to 1750° F. to promote the formation of unsaturated hydrocarbons, quenching the resultant gaseous products with cool naphtha derived from the same source as the naphtha being reformed, commingling admixed gaseous products and naphtha with the hot products from said reforming stage and digesting the commingled products at a temperature of from 700° to 1000° F. to promote interaction between unsaturated hydrocarbon constituents of said commingled products, withdrawing the resultant products and fractionat-

ing them to recover normally liquid products therefrom.

3. The process which comprises subjecting naphtha to an elevated temperature in the absence of normally gaseous hydrocarbons and substantial amounts of higher-boiling constituents to reform said naphtha, subjecting hydrocarbon gases containing paraffin hydrocarbon constituents free of products of combustion to an elevated temperature to effect the formation of unsaturated hydrocarbons therefrom, quenching the resultant gaseous products with cool naphtha, commingling admixed gaseous products and naphtha with the hot products from said reforming stage and digesting the commingled products at an elevated temperature to promote interaction between unsaturated hydrocarbon constituents of said commingled products, withdrawing the resultant products and fractionating them to recover normally liquid products therefrom.

4. The process which comprises subjecting naphtha to an elevated temperature in the absence of normally gaseous hydrocarbons and substantial amounts of higher-boiling constituents to reform said naphtha, subjecting hydrocarbon gases containing paraffin hydrocarbon constituents free of products of combustion to an elevated temperature to effect the formation of unsaturated hydrocarbons therefrom, quenching the resultant gaseous products with cool naphtha derived from the same source as the naphtha being reformed, commingling admixed gaseous products and naphtha with the hot products from said reforming stage and digesting the commingled products at an elevated temperature to promote interaction between unsaturated hydrocarbon constituents of said commingled products, withdrawing the resultant products and fractionating them to recover normally liquid products therefrom.

PIKE H. SULLIVAN.
